United States Patent Office

Des. 176,368
Patented Dec. 13, 1955

176,368

TELEVISION ANTENNA

Marvin P. Middlemark, Forest Hills, N. Y.
Application April 19, 1955, Serial No. 35,574

Term of patent 14 years
(Cl. D26—14)

Fig. 1 is a front perspective view of a television antenna showing my new design;

Figure 2 is a rear perspective view.

The bottom side of the antenna is plain in appearance.

I claim:

The ornamental design for a television antenna, substantially as shown and described.
